WATER CLOSET CONSTRUCTION

Max Grunt, Summit, N. J.

Application September 11, 1942, Serial No. 458,016

8 Claims. (Cl. 4—10)

The present invention relates to improvements in plumbing fixtures and has reference more particularly to a water closet construction.

One of the important objects of the present invention is to provide a water closet structure that is formed of non-critical material and is further adapted for use in low cost housing projects, or in knock-down buildings.

Another important object of the invention resides in the provision of a concrete slab adapted for disposition within a wall between a pair of spaced studs, wherein the slab is specially constructed to coact with a water closet bowl, the latter being also formed of concrete, and wherein in the slab is formed with a water tank, there being means provided for supplying water to the tank from a suitable source of supply and for discharging the water from the tank into the interior of the bowl.

A still further object is to provide a water closet construction embodying a novel waste conduit having slidable and detachable engagement with the bottom of the water closet bowl, and which waste conduit is also formed of concrete material.

A still further and important object is to provide a construction of the above mentioned character wherein the use of the conventional metal pipes and fittings as are ordinarily associated with a water closet is eliminated, thereby rendering the device inexpensive and capable of quick and easy assembly.

Other objects and advantages of the present invention will become apparent during the course of the following description, when taken in connection with the accompanying drawing.

In the drawing forming a part of this specification and in which like reference characters designate corresponding parts throughout the several views:

Figure 1 is a vertical sectional view taken approximately on the line 1—1 of Figure 2;

Figure 2 is a vertical sectional view taken approximately on the line 2—2 of Figure 1, looking in the direction of the arrows;

Figure 3 is a horizontal section taken approximately on the line 3—3 of Figure 1, looking downward;

Figure 4 is a similar section taken approximately on the line 4—4 of Figure 1, also looking downward;

Figure 5 is a horizontal section taken approximately on the line 5—5 of Figure 1, and

Figure 6 is a detailed view showing one of the

conduits provided with a metal pipe liner, as a modification.

In the drawing, wherein there is shown a preferred embodiment of my invention, the numeral 5 1 designates generally a wall of a building and a pair of spaced vertical studs 2 form a space 3 therebetween, the purpose of which will be presently described. The floor is designated by the numeral 4.

Fitted within the space or recess 3 between the spaced studs 2 is the elongated concrete slab 5. This slab is formed with a substantially rectangular shaped pocket 6 in the front face of the lower portion thereof. Also formed in the front face of the lower portion of the concrete slab on opposite sides of the central pocket 6 are the side compartments 7 and 8. The latter may be used for the reception of various articles, such as toilet paper, syringes, etc.

20 Formed integrally with the upper portion of the concrete slab 5 and projecting outwardly from the front face thereof is the water tank 9. A removable cover 10 is provided for the open top of the water tank. A discharge conduit 11 extends from the bottom of the water tank 9 to the top of the pocket 6. A gravity seated valve 12 normally rests on the upper end of the conduit 11 within the tank 9. The valve stem associated with the valve 12 is designated by the numeral 13 and is slidable within a suitable guide 14 within the tank. An actuating cable 15 is connected to the upper end of the valve stem 13 and is disposed through a suitable guide 17 that depends from the top portion of the water tank and the outer end of this cable extends through an opening 18 formed in the front side of the water tank adjacent the top thereof.

The slab 5 is formed with a vertically extending conduit 19 that extends from the bottom of the slab and the upper end of this conduit communicates with the rear lower portion of the water tank 9 as at 20. The lower end of the water supply conduit 19 has connection with a suitable water supply pipe 21 that is disposed beneath the floor 4 and this supply pipe has connection with a suitable source of water supply, (not shown).

40 A valve 22 is associated with the water supply line 21 and a foot operated treadle 23 that extends upwardly through the floor, controls the opening and closing of the valve 22, in the manner also to be hereinafter more fully described.

The upper portion of the concrete slab 5 in the rear of the water tank 9 is formed with a by-pass conduit 24, the upper end of this by-pass con-

duit having communication with the top portion of the water tank 9, while the lower end of this by-pass conduit communicates with the discharge conduit 11.

It is to be understood that the various conduits formed in the concrete slab 5 are produced by the usual plastic molding methods and suitable cores are employed for forming the various conduits, it being understood that these cores are removed after the plastic material has set.

Also forming a salient part of the present invention is the concrete water closet bowl 25. The rear body portion 26 of the water closet bowl is substantially rectangular in cross section and is adapted to fit snugly within the pocket 6 provided therefor in the lower portion of the concrete slab 5, in the manner as clearly shown in the drawing.

The receptacle portion of the bowl is denoted by the numeral 27 and water is supplied thereto from the rim portion 28 in the conventional manner. The top of the water closet bowl may be either finished off to form a seat portion or if desired, a separate seat may be mounted thereon.

A conduit 29 is formed in the top of the body portion 26 for affording communication between the discharge conduit 11 that leads from the water tank to the water supply conduit in the rim 28 of the water closet bowl 25. It is, of course, understood that when the water closet bowl is properly fitted into the pocket 6, the conduits 11 and 29 will be in vertical registration with each other. If desired, the joint between the top of the body portion 26 and the adjacent portion of the pocket 6 may be cemented or otherwise sealed to prevent any water from discharging between these two elements.

The water closet bowl 25 is provided with the conventional trap 30 that has communication with the receptacle portion 27 and the discharge conduit 31 that is formed in the body portion of the bowl. The lower end of the discharge conduit 31 extends to the base of the bowl and has communication with the horizontally extending waste conduit 32, through the opening 33.

This waste conduit 32 is also formed of concrete material and is disposed horizontally beneath the floor 4. The upper portion of this conduit is formed with laterally extending flanges 34 at the sides thereof for slidably engagement with the channeled portions 35 that project downwardly from the face of the bowl and body portion thereof, in the manner as is more clearly illustrated in Figure 2.

The concrete waste conduit 32 is further formed with the vent 36 and the latter has communication with the interior of the conduit, as at 37. The inner end of the conduit 32 is closed, while the other end is adapted for connection with the conventional waste or sewage pipe not shown.

It is also understood that the conduits formed in the water closet bowl are produced in the same manner as are the conduits in the concrete slab 5.

When the parts are assembled in the manner as shown in Figure 1 of the drawing, the occupant of the bowl steps upon the treadle 23, thereupon causing water to be delivered to the water tank 9 through the supply pipe 21 and the conduit 19. This operation continues until the tank has been filled to such extent that the water will overflow into the by-pass 24 and will flow back into the receptacle 27, thus indicating to the user that the water tank is properly filled.

By pulling on the cable 15, the valve 12 will be unseated, thus permitting the water to be discharged from the tank 9 into the conduits 11 and 29 and finally delivered to the receptacle 27 of the water closet bowl 25 and the contents of the receptacle 27 are ultimately discharged into the waste conduit 32 through the discharge conduit 31 and opening 33.

It will thus be seen from the foregoing description that I have provided a water closet construction that does not require the use of any critical metals and due to its simplicity, the same may be molded from concrete or any other suitable plastic material at a very low cost. Such a structure is particularly desirable in the installation of water closets in low cost buildings and apartments, as well as portable knock-down houses.

A structure of the above-mentioned character will, at all times, be positive and efficient in its operation and can be very easily assembled.

If necessary, the conduits formed in the cement slab and water closet bowl may be lined with lead pipes, such as is indicated at 38 in Figure 6, although it is preferred not to use any metal liners in the conduits.

While I have shown the preferred embodiment of my invention, it is to be understood that various changes in the size, shape and arrangement of parts may be resorted to without departing from the spirit of the invention and the scope of the appended claims.

Having thus described my invention, what I claim is:

1. The combination with a wall having a recess formed therein, a slab arranged in said recess, said slab being formed with a pocket in the lower front side thereof, a water closet bowl having its rear portion fitted in the pocket in said slab, a water tank carried by the upper portion of the slab, means for supplying water to the tank, means for communicatingly connecting the water tank with the interior of the bowl when the latter is positioned in the slab pocket, and a waste conduit in communication with the bowl.

2. The combination with a wall having a recess formed therein, a slab arranged in said recess, said slab being formed with a pocket in the lower front side thereof, a water closet bowl having its rear portion fitted in the pocket in said slab, a water tank carried by the upper portion of the slab, means for supplying water to the tank, means for communicatingly connecting the water tank with the interior of the bowl when the latter is positioned in the slab pocket, and a waste conduit in communication with the bowl, said slab and bowl being formed of plastic material.

3. The combination with a wall having a recess formed therein, a slab arranged in said recess, said slab being formed with a pocket in the lower front side thereof, a water closet bowl having its rear portion fitted in the pocket in said slab, a water tank carried by the upper portion of the slab, means for supplying water to the tank, means for communicatingly connecting the water tank with the interior of the bowl when the latter is positioned in the slab pocket, and a waste conduit in communication with the bowl, said slab and bowl being formed of plastic material, the water tank being formed integral with the slab.

4. The combination with a wall having a recess formed therein, the sides of which are formed by a pair of studs, a concrete slab fitted in said recess between the studs, the lower portion of said slab having a pocket formed in its front face, a water

closet bowl having its rear body portion fitted in said pocket and being also formed of concrete, a water tank formed integrally with the upper front portion of the slab, a water supply conduit formed in the slab and communicating at its upper end with the tank, the lower end of said conduit having connection with a water supply line, coacting conduits formed in the slab and bowl for delivering water from the tank to the interior of the bowl, a valve for controlling the discharge of the water from the tank to the last mentioned conduits, and a waste conduit for receiving the discharge of the water closet bowl.

5. The combination with a wall having a recess formed therein, the sides of which are formed by a pair of studs, a concrete slab fitted in said recess between the studs, the lower portion of said slab having a pocket formed in its front face, a water closet bowl having its rear body portion fitted in said pocket and being also formed of concrete, a water tank formed integrally with the upper front portion of the slab, a water supply conduit formed in the slab and communicating at its upper end with the tank, the lower end of said conduit having connection with the water supply line, coacting conduits formed in the slab and bowl for delivering water from the tank to the interior of the bowl, a valve for controlling the discharge of the water from the tank to the last mentioned conduits, a waste conduit for receiving the discharge of the water closet bowl, and a by-pass conduit formed in the slab and extending from the top of the water tank to the discharge conduits.

6. The combination with a wall having a recess formed therein, the sides of which are formed by a pair of studs, a concrete slab fitted in said recess between the studs, the lower portion of said slab having a pocket formed in its front face, a water closet bowl having its rear body portion fitted in said pocket and being also formed of concrete, a water tank formed integrally with the upper front portion of the slab, a water supply conduit formed in the slab and communicating at its upper end with the tank, the lower end of said conduit having connection with a water supply line, coacting conduits formed in the slab and bowl for delivering water from the tank to the interior of the bowl, a valve for controlling the discharge of the water from the tank to the last mentioned conduits, a discharge conduit for the bowl, and a waste carrying-off conduit slidably connected with the bottom of the bowl and having communication with the lower end of said bowl discharge conduit.

7. The combination with a wall having a recess formed therein, the sides of which are formed by

a pair of studs, a concrete slab fitted in said recess between the studs, the lower portion of said slab having a pocket formed in its front face, a concrete water closet bowl having its rear body portion fitted in said pocket, a conduit formed in the top of the rear portion of the bowl and having communication with the interior thereof, said bowl being formed with a discharge conduit extending to the bottom thereof, a water tank formed integrally with the upper front portion of the slab, a discharge conduit leading from the bottom of the water tank to the top of a pocket for communication with the aforementioned conduit in the bowl when the bowl is seated in said pocket, 15 said slab being formed with a water supply passage having its upper end in communication with the lower portion of the water tank, a source of water supply connected to the lower end of the passage, a valve for controlling the discharge of the water from the tank to the aforesaid communicating conduits, and a waste carrying-off conduit connected with the bottom of the bowl and having communication with the lower end of the bowl discharge conduit.

25 8. The combination with a wall having a recess formed therein, the sides of which are formed by a pair of studs, a concrete slab fitted in said recess between the studs, the lower portion of said slab having a pocket formed in its front face, 30 a concrete water closet bowl having its rear body portion fitted in said pocket, a conduit formed in the top of the rear portion of the bowl and having communication with the interior thereof, said bowl being formed with a discharge conduit extending to the bottom thereof, a water tank formed integrally with the upper front portion of the slab, a discharge conduit leading from the bottom of the water tank to the top of a pocket for communication with the aforementioned conduit in the upper rear portion of the bowl when the bowl is seated in said pocket, said slab being formed with a water supply passage having its upper end in communication with the lower portion of the water tank, a source of water supply connected to the lower end of the passage, a valve for controlling the discharge of the water from the tank to the aforesaid communicating conduits, 45 said slab being formed with a by-pass conduit that communicates at its upper end with the upper portion of the water tank and at its lower end with the discharge conduit leading from the bottom of the tank, and a waste carrying-off conduit connected with the bottom of the bowl and having communication with the lower end of the bowl discharge conduit.

55 MAX GRUNT.
